UNITED STATES PATENT OFFICE

2,592,149

THERAPEUTIC PREPARATION COMPRISING
BENZYL CINNAMATE AND VITAMIN A

Jacob Jacobson, New York, N. Y.

No Drawing. Application April 9, 1949,
Serial No. 86,592

6 Claims. (Cl. 167—65)

1

This invention relates to therapeutic preparations adapted for subcutaneous or intramuscular injection containing vitamin A and a benzyllic compound, such as benzyl alcohol or a benzyl ester, in a suitable vehicle.

The therapeutic properties of the benzyl ester of cinnamic acid have been extensively investigated and the results are described in many publications among which may be mentioned the following:

Comptes Rendue Soc. de Dermatologie of February 9, 1922—Articles by Darier and Jeanselme and Jacobson.

Bulletin et Mem. de la Soc. Med. des Hop., Reports of the Sessions of October 23, 1925, March 25, 1927, and April 19, 1929.

La Presse Medicale, of March 13, 1929—Article by Gosset, Gutmann, and Iahel.

Paris Medical, of October 25, 1930—Article by Levy-Solal, et al.

Publication by Societe d'Ophtalmologie de Paris of February 1931—Article by Chevallereau and Segal.

La Tunisie Medicale, April, 1932—Report of the Commission de Tunisie.

Revenue Internationale du Trachome, of January, 1932, and April, 1933, by Jean-Sedan.

Archives de Medecine et de Pharmacie Militaires of February, 1933—Article by Barrel and Luc.

Revue Internationale du Trachome of April, 1933—Article by Junes.

Bulletin of the Academy of Medicine—Report of the Session of July 18, 1933, volume 110, No. 28 on "Regression des keratites, etc."

The preparation ordinarily employed consisted of 3.2 parts of benzyl cinnamate in solution in 100 parts of olive oil by volume.

In my prior Patent No. 2,081,934 a composition is disclosed which obtains better results. This composition is one in which the 3.2 parts of benzyl cinnamate is reduced and in part replaced by other ingredients which contribute one or both of the benzyl alcohol or cinnamic acid radicals. For instance, such a composition may be made from a mixture of about 20 grams of benzyl cinnamate, about 10 to 15 cc. of benzyl alcohol and about 2 cc. of ethyl cinnamate. The mixture of these components is suspended in olive oil in approximately 3.2 parts of the mixture to about 100 parts of the olive oil suspension. The preparation is then placed in ampules and sterilized. The ordinary dose for a normal patient is from $\frac{1}{2}$ to 1 cc., and the ordinary dose for a child is $\frac{1}{4}$ cc. The preferred administration is by way of intramuscular and subcutaneous injection.

2

The exact manner in which the benzyl cinnamate or benzyl alcohol and cinnamic acid acts is not exactly known, although its biological and physiological properties are manifest. Clinical experiments have demonstrated that the solution of the benzyl cinnamate or its chemical components favors the absorption or the elimination of chronic inflammatory lesions regardless of their location in the organism. I have studied the vascular reaction which is manifest upon the administration of benzyl cinnamate and from clinical and experimental work on the corneal opacities, I have found that the action is characterized by a dilatation of the existing blood vessels, the opening of blocked blood vessels and the appearance of newly formed blood vessels.

The composition has been particularly effective in the treatment of certain forms of deafness, tinnitus and dizziness.

J. Jacobson: Archives of Oto-Laryngol., October, 1943, vol. 38, pp. 365-368.

25 J. Jacobson: The Eye, Ear, Nose, and Throat Monthly, 23:395-399, October 1944, and volume XXV, No. 11, pp. 544-553, November 1946.

Samuel Kopetsky: Deafness, Tinnitus, Dizziness, Nelson and Son, 1948.

30 In deafness, caused by a chronic inflammatory lesion of the middle ear, the benzyl cinnamate removes the obstacle created by chronic inflammation to the passage of the sound waves and the nerve endings are able to receive more stimulation. Therefore, the hearing is improved.

35 The use of the composition has been extended to the treatment of chronic salpingitis as reported in the following publication:

Morris I. Eisenstein, M. D., and George J. Bendo, M. D.: "Treatment of Chronic Salpingitis with Benzyl Cinnamate Ester (Jacobson's Solution)," The American Journal of Surgery, vol. LXXIV, No. 2, August, 1947, pages 200-204.

40 In accordance with my invention I have now discovered that a composition containing benzyl cinnamate or its chemical components, as described in my patent and in the prior publications, to which vitamin A has been added, has markedly superior properties in achieving therapeutic properties.

45 The following examples are illustrative of the compositions made in accordance with my invention:

Example 1

50 An olive oil suspension containing 3.2 parts of benzyl cinnamate in 100 parts by volume of the

suspension has added to it vitamin A in the proportion of 10,000 units to each 1 cc. of the suspension.

Example 2

An olive oil suspension of 2.5% of benzyl cinnamate has vitamin A added to it in the amount of 10,000 units of vitamin A for each 1 cc. of the suspension.

Example 3

A mixture of 20 grams of benzyl cinnamate and 15 cc. of benzyl alcohol is suspended in olive oil in proportions approximately 3.2 parts of the mixture in 100 parts of the suspension. To this is added vitamin A in an amount of 10,000 units per 1 cc. of the suspension.

Example 4

An olive oil suspension of 1.5% of benzyl cinnamate and 2.0% of benzyl alcohol has added to it 10,000 units of vitamin A per 1 cc. of the mixture.

Example 5

Olive oil containing 2.5% benzyl alcohol has added to it 10,000 units of vitamin A per 1 cc. of the mixture.

Any of the above examples may be modified by adding thereto 1/2% of ethyl cinnamate.

The essential ingredients of the composition of my invention include vitamin A and benzyl alcohol or a benzyl ester yielding benzyl alcohol such as benzyl cinnamate, or components furnishing these radicals, in an oil suspension. The benzyl cinnamate may be replaced in part or entirely by other compounds which furnish its chemical components and are therefore its equivalent. The amount of the benzylic compound or the chemical components which compose it may vary from 2% to 5% of the oil suspension, the optimum being from 2.5% to about 3.2%. The amount of vitamin A may vary from about 7,500 to 12,500 units per cc. of the oil suspension. The amount within this range is not thought to be critical.

The amounts of all of the ingredients may be varied plus or minus 25%. The amounts are not critical, but the proportions expressed in the examples are the optimum concentrations for the usual purposes.

In place of olive oil, any other non-drying fatty oil may be used which is a conventional equivalent as a base for therapeutic compositions for subcutaneous or intramuscular injection.

The efficacy of the composition of my invention has been demonstrated in treating cases of deafness due to an inflammatory condition and certain forms of tinnitus. Numerous cases which are refractory to treatment with preparations

containing various mixtures of benzyl cinnamate or benzyl alcohol and ethyl cinnamate, respond much better to the composition of my invention. The results are obtained in a shorter time; they are more permanent and the percentage of the refractory cases of tinnitus is markedly reduced. The composition of my invention is efficacious in many refractory cases that do not respond to benzyl cinnamate, and are not affected at all by vitamin A alone.

The use of the preparation of my invention is applicable not only to the treatment of deafness but also to the various chronic inflammatory lesions, where the composition of my previous patent has been used, and with better results.

I claim:

1. A therapeutic composition comprising benzyl cinnamate in olive oil containing 2 to 5 parts of benzyl cinnamate per 100 parts of the suspension and 7,500 to 12,500 units of vitamin A per cc. of the suspension.

2. A therapeutic composition comprising olive oil containing 2.5% to 3.2% benzyl cinnamate and 7,500 to 12,500 units of vitamin A per cc.

3. A therapeutic preparation, the essential ingredients of which are olive oil, about 3.2% benzyl cinnamate, and about 10,000 units of vitamin A per cc.

4. A therapeutic composition comprising olive oil and as essential therapeutic ingredients a mixture of benzyl cinnamate and benzyl alcohol and 7,500 to 12,500 units of vitamin A per cc.

5. A therapeutic composition comprising olive oil and as essential therapeutic ingredients a mixture of benzyl cinnamate, benzyl alcohol and ethyl cinnamate, and 7,500 to 12,500 units of vitamin A per cc.

6. A sterilized ampule-contained therapeutic preparation constituted of an olive oil suspension of a mixture containing benzyl cinnamate ester and benzyl alcohol in the approximate relation of 20 grams of the former in 15 cc. of the latter and with a total of suspended material approximating 3.2 parts in 100 parts of the suspension and about 7,500 to 12,500 units of vitamin A per cc. of the oil suspension.

JACOB JACOBSON.
